JAMES A. HENSON, OF AUBREY, TEXAS.

BACK-BAND BUCKLE.

979,490.

Specification of Letters Patent. Patented Dec. 27, 1910.

Application filed October 18, 1909. Serial No. 523,290.

To all whom it may concern:

Be it known that I, JAMES A. HENSON, citizen of the United States, residing at Aubrey, in the county of Denton and State 5 of Texas, have invented certain new and useful Improvements in Back-Band Buckles, of which the following is a specification.

This invention has relation to backband buckles and new and useful improvements 10 therein.

The object of the invention is to provide a buckle which will hold in position either on a web or leather backband and so arranged that an increased pull will act to tighten the 15 engagement of the buckle with the backband instead of loosening the same and in carrying out this feature will also provide teeth engaging on both sides of the backband in staggered relation.

20 Finally the object of the invention is to provide means of the character described that will be strong, durable, efficient, and easy of operation, simple and comparatively inexpensive to construct, and also in which 25 the several parts will not be likely to get out of working order.

With the above and other objects in view, the invention has relation to certain novel features of construction and operation, an 30 example of which is described in this specification and illustrated in the accompanying drawings, wherein:

Figure 1. is an elevation of the buckle, Fig. 2. is a vertical section on the line $\alpha-\alpha$ 35 of Fig. 1. showing a portion of the backband in the buckle, and Fig. 3. is a side elevation of a portion of the buckle and backband.

In the drawings the numeral 1 designates the buckle and 2, the backband. The buckle 40 is formed of any preferred metal and suitably finished.

In constructing the buckle a broad base plate is provided. The base plate at its lower end is contracted to form a central 45 depending loop or hook 4. This hook is produced by bending up the metal and directing it over the contracted portion as shown in Fig. 2. The end of the hook is bent slightly inward to form a spring locking tongue for the purpose hereinafter described.

At the upper end and on opposite sides of the base plate, ears 6 are provided and project at substantially right angles to the 50 plate. These ears are arranged to receive the trunnions 7 of a flat clamp 8, permitting

the clamp to be swung open to receive the backband and close to hold it in the buckle. The clamp is also contracted at its lower end to produce a depending central portion 60 which terminates in a stop 9 directed inwardly from the clamp and adapted to impinge the base plate at a point adjacent the spring tongue 5. The lower face of the stop is roughened or provided with teeth as indicated at 10 and with which the end of the tongue 5 engages to lock the clamp in position. It is obvious that by pressing inward on the tongue, the clamp is released and may be swung outward. 70

Transversely of the base plate a curved opening 11 is provided and is of sufficient width to freely receive the backband 2. Along the upper edge of the opening teeth or projections 12 are provided. These teeth 75 are bent slightly so as to project toward the clamp. In the clamp similar teeth 13 are provided and bent slightly inward toward the base plate. However the teeth 13 are so disposed as to project in staggered relation 80 to the teeth 12 and with their points substantially over the intersections of the teeth 12. This disposition and arrangement of the teeth is very important and is one of the best features of my invention for the 85 reason that when the backband is passed through the buckle as shown in Fig. 2 the teeth will bite into it on both sides and the teeth on one member will have a tendency to force the backband into the spaces between the teeth of the other member and thus firmly hold the buckle against sliding or displacement on the backband irrespective of the fact that the backband is made 90 of leather or webbing. It is also obvious 95 that either an upward pull on the backband or a downward pull on the buckle that will cause the teeth to more firmly engage the backband.

What I claim is:

100 The combination in a backband buckle, of a base plate flat throughout its length, ears turned up from the plate at each side of one end, the opposite end of the base plate being cut away at each side, a hook formed 105 from the cut away end of the plate and bent thereon, a spring locking tongue extending inward at an angle from the hook, the base plate having a transverse opening with one curved side and one straight side, teeth projecting from the plate into the opening on the straight side, the teeth having their 110

points bent upward, a flat clamp plate having trunnions at one end engaging in the ears, the clamp plate having a transverse opening out of alinement with the opening of the base plate, teeth extending into the opening of the clamp plate, and having their points directed downward and in staggered relation to the teeth of the clamp plate, and a stop bent from the clamp plate 10 at right angles and provided with a rough-

ened face engaged by the spring locking tongue.

In testimony whereof I have signed my name to this specification in the presence of two subscribing witnesses.

JAMES A. HENSON.
